UNITED STATES PATENT OFFICE

HELEN GERTRUDE LEYTON AND GEOFFREY BERTRAND LEYTON, OF OXFORD, ENGLAND

KNITTING MACHINE

Application filed January 3, 1930, Serial No. 418,285, and in Great Britain December 31, 1928.

This invention refers to improvements in or relating to knitting machines, and it has for its primary object to provide a machine which will produce stockings and other knitted fabrics or articles which will not be liable to "ladder" when damaged or worn.

A knitting machine has been previously proposed in which, for the production of patterned fabric, colored threads are incorporated with the web at intervals around the needle cylinder by means of stationary thread guides, the cylinder being rotated for the production of spiral formation.

The invention is applicable to both hand and power driven machines for domestic or factory use, of both the circular or flat or straight type.

In a knitting machine according to the invention, there is provided for the purpose of producing non-laddering fabric, a series of thread guides carried upon a dial or plate and disposed adjacent to the usual knitting needles, said thread guides being operated to wrap a separate auxiliary locking thread around each knitting needle, said plate being shogged once for each course of stitches so that the auxiliary locking thread from each needle passes to the next adjacent needle, said auxiliary locking thread, after locking a stitch, forming a loop which is knitted off in the next course of material.

The machine may be of the usual stationary cylinder type, a slotted dial plate being provided adjacent to the hooks of the cylinder needles and carrying radial thread guides which are operated by a cam rotating with the needle cam, said slotted dial being disposed eccentrically of the needle cylinder and moving in a circular path around the axis of said needle cylinder.

The invention is also applicable to a machine of the flat or straight type, there being provided adjacent to the eyes of the knitting needles a series of thread guides carried upon a plate; which after every course of stitches has been knitted, is moved bodily in a circular path so that threads carried by the thread guides are wrapped around the knitting needles for producing a locking stitch when the next row of stitches is produced.

If desired, the shogging means may comprise a one-tooth pinion engaging a toothed ring carried upon bearer rollers, and an upwardly extending arm adapted to engage a member for communicating the motion of 55 said ring to the slotted dial plate.

A further object of the invention is to provide a non-laddering fabric comprising a groundwork of ordinary knitted web with diagonally or helically arranged auxiliary 60 locking threads interlocked, as hereinafter described and illustrated.

In order that the invention may be clearly understood, it is hereinafter described with reference to the accompanying drawings, in 65 which:—

Figure 1 is a diagrammatic plan view of a circular knitting machine adapted to produce non-laddering fabric;

Figure 2 is a corresponding side elevation;

Figure 3 is a sectional elevation of the device used for incorporating the auxiliary locking threads, the dial being shown in inclined relation to the upper plane of the cylinder;

Figure 4 is a plan view of the slotted dial showing several thread guides in position;

Figure 5 is a sectional elevation of Figure 4, showing the arrangement of the auxiliary locking threads and thread guides;

Figure 6 is a diagrammatic plan view illustrating the application of the invention to knitting machines of the flat or straight type; and

Figure 7 is a diagram illustrating a portion 85 of knitted fabric produced in accordance with the invention.

As shown, and referring more particularly to the arrangement shown in Figures 1 to 5 of the accompanying drawings, it will be seen 90 that the needle cylinder 10 carrying the knitting needles is of the usual type for knitting plain fabric of tubular formation. The machine shown comprises a stationary needle cylinder 10 and a revolving needle cam 22 95 carrying the usual yarn guide 36 for feeding the yarn to the cylinder needles 11.

A mechanism according to the invention, suitable for this type of machine, comprises a circular dial 12 provided centrally with 100

a sleeve 16 which is mounted rotatably within the end of an arm 14 attached to the revolving needle cam 22 by means of a bracket 13, and arranged with locking means 37 and 38 in order that the center of the circular dial 12 may be adjusted with respect to the needle cylinder 10 so that the circular dial 12 may be eccentric thereto or inclined to the plane of the upper face of said cylinder 10, this being accomplished by rotating the arm 14 within the bracket 13, the lower end of which is slotted for vertical adjustment and may be spaced from the needle cam 22, if desired, by packing pieces (not shown).

15 The upper surface of the circular dial 12 is formed with radial slots 39, equal in number to the cylinder needles 11, in each of said slots 39 being mounted a thread guide 15 formed at its outer end with an eye 40 for carrying one or more auxiliary locking threads 19, and provided adjacent to its other end with a butt 21 which engages with a cam groove in a dial cam 20 mounted upon the sleeve 16 but caused to rotate with the arm 14 by the engagement therewith of a pin 33. The upper end of the sleeve 16 is formed with a circular plate 17 carrying a number of pins 18 for the accommodation of spools (not shown) carrying the thread supplies for the 25 auxiliary locking threads 19, each of which passes toward the center of said circular plate 17, downwardly within the sleeve 16, and thence outwardly, past the under surface of the circular dial 12 to the eye 40 of its 30 corresponding thread guide 15.

35 The circular plate 17 and the circular dial plate 12 are shogged once for each course of stitches, through an angle equal to that between two adjacent cylinder needles 11 by 40 means of an adjustable support or upstanding finger 23 which is attached at 24 to a circular rack 25 which is internally toothed, as shown at 26, and which is held in position by means of a plurality of V-grooved rollers 45 27 engaging its bevelled periphery 28. The teeth 26 are engaged by a cog or spur wheel 29 which is rotated from any convenient part of the driving mechanism of the machine, as will be readily understood. Thus the turning 50 movement of the rack 25 will be transmitted to the parts 17 and 12 through the medium of the finger 23 and the horizontal arm 30 the outer end of which passes freely through an eye 31 in the upper end of the 55 finger 23, whilst the inner end of same is connected to the plate 17 by means of a horizontal pivot pin 32, which arrangement allows for the eccentricity or tilting of the parts.

60 In operation, the needle cam 22 rotates about the needle cylinder 10, thus operating the cylinder needles 11 in the usual manner. This movement also causes the axis of the circular dial 12 to move in a circular path, i. e., to trace out the surface of a cylinder or cone, according to whether the axis of the cir-

70 cular dial 12 is parallel with, or inclined to, the axis of the needle cylinder 10, respectively. This motion, which is timed correctly with respect to the operation of the cylinder cam 22 and the dial cam 20, causes the auxiliary locking threads 19 each to be wrapped around one of the cylinder needles 11 at an inoperative portion of the knitting cycle of said cylinder needles 11, once at each revolution of the cams 20 and 22. In this way the auxiliary locking threads become incorporated with the fabric when the existing loops are passed off of the cylinder needles 11, and the continuation of each auxiliary locking thread 19 is, at the next revolution of the 75 cams 20 and 22, wrapped around the next adjacent needle, due to the shogging of the circular dial plate 12 by the circular rack 25.

80 The resulting fabric thus comprises a 85 groundwork of ordinary knitted web 41 with diagonally or helically arranged auxiliary locking threads 19 interlocked, as shown in Figure 7, where, for clearness, one auxiliary locking thread 19 only is shown. The auxiliary locking threads 19 prevent laddering of the material when damaged or worn, and also strengthen it without in any way impairing its flexibility.

90 As, according to the invention, each auxiliary locking thread is applied to the corresponding knitting needle while the latter is inoperative, i. e., at the completion of a stitch thereon, the invention may easily be applied to a flat or straight type of knitting machine. Thus, in the case of a machine having fixed 95 needles, the auxiliary locking thread guides are carried firmly upon a longitudinal bar 34 which is adapted to be moved in connection with the existing knitting needles so as to lay auxiliary threads about the needles at the 100 completion of each row of stitches. To this end auxiliary locking thread guides 42 may be attached to a horizontal bar 34 which is caused to move in a circular path so that the 105 thread guides 42 as they are simultaneously 110 projected pass the auxiliary locking threads around the heads of the knitting needles. Thus the bar carrying the additional needles 115 may be mounted at or near its ends on a pair of cams or eccentrics 35, so that it will be given the required motion, the cams or eccentrics receiving their movement from the mechanism of the machine through the medium of suitable gearing (not shown).

120 The auxiliary locking threads may be caused to pass through the knitted web in a diagonal or oblique direction by shogging the plate 34, together with the operating eccentrics 35, through a distance equal to that 125 between two adjacent needles of the machine, the number of thread guides being in excess of the number of knitting needles, so that after the plate 34 has been shogged a predetermined number of times toward one end of the machine, the shogging means may be 130

caused to reverse so as to move the plate 34 at each operation toward the other end of the machine. This produces a fabric in which the locking threads pass through the fabric 5 diagonally, alternately in the one direction and then in the other.

It will be obvious to those skilled in the art that various modifications may be made in the construction and arrangement of the 10 machines. Also, the invention may be carried out on any type of machine, including machines with bearded needles, the process of knitting in the locking thread being the same in any machine.

15 What we claim is:—

1. A knitting machine including a needle cylinder, a slotted dial mounted for vertical, eccentric and inclined adjustment with respect to the cylinder, thread guides movable 20 radially in the dial, a cam for operating the thread guides, and means connected with the dial for supporting a plurality of spools carrying threads to be passed through the thread guides.

25 2. In a knitting machine, a needle cylinder, a radially slotted dial, means for adjustably supporting the dial with respect to the needle cylinder, said means providing vertical, lateral and inclined adjustment of the 30 dial with respect to the needle cylinder, a spool carrying support movable with the dial, a series of thread guides movable in the slots in the dial and terminally formed to permit the passage of the thread from spools on said 35 spool carrying support, and a cam movable relative to the dial for successively operating the thread guides.

3. In a knitting machine, a needle cylinder, a radially slotted dial, thread guides movable 40 in the slots in the dial and formed with terminal eyes, a hollow post rising from the dial, a thread carrying support at the upper end of the post, a cam mounted on the post and movable relative to the dial for operating 45 the thread guides, and means cooperating with the post for supporting the dial for adjustment vertically, radially and for inclination with respect to the needle cylinder.

4. In a knitting machine, a needle cylinder, 50 a radially slotted dial, thread guides movable in the slots in the dial and formed with terminal eyes, a hollow post rising from the dial, a thread carrying support at the upper end of the post, a cam mounted on the post 55 and movable relative to the dial for operating the thread guides, and means cooperating with the post for supporting the dial for adjustment vertically, radially and for inclination with respect to the needle cylinder, said 60 supporting means serving to compel relative movement of the cam with respect to the dial.

5. A knitting machine including a needle cylinder, a slotted dial mounted for vertical, eccentric and inclined adjustment with respect 65 to the cylinder, thread guides movable

radially in the dial, a cam for operating the thread guides, means connected with the dial for supporting a plurality of spools carrying threads to be passed through the thread guides, means for shogging the dial comprising 70 a one-tooth pinion, a toothed ring carried in bearing rollers, an upwardly extending arm carried by the ring, and a member carried by the arm and extending to and serving to operate the dial.

75 In testimony whereof we have hereunto signed our names.

HELEN GERTRUDE LEYTON.
